UNITED STATES PATENT OFFICE.

ERICH KINDERMANN, OF BERLIN-REINICKENDORF, GERMANY, ASSIGNOR TO
A. BORSIG G. M. B. H., OF BERLIN-TEGEL, GERMANY.

REFRIGERATING SYSTEM.

Application filed March 10, 1926, Serial No. 93,685, and in Germany March 10, 1925.

My invention refers to the art of refrigeration by absorption and its particular object is to provide means for removing the water from the evaporating vessel of a periodically working absorption refrigerating machine.

As is well known to those skilled in the art, in refrigerating machines of this type which are arranged to be tipped about an axis situated below their centre of gravity and which are reversed automatically by the distribution of the refrigerating liquid between the evaporator and the generator absorber, such liquid as may have passed through, is returned from the evaporator into the generator absorber by means of the evaporator liquid which, when the absorption period has come to an end and the machine swings back into its initial position, will flow from the evaporator which is disposed at a higher level, to the generator absorber. Now this mode of operating requires the machine to oscillate through a very large angle or else the design of the machine becomes very complicated and the evaporation vessels become unduly large and are not sufficiently utilized.

On the other hand the overflow for the refrigerating liquid in the evaporator, which is provided in stationary machines, cannot be utilized in oscillating machines in which the end of the heating period is automatically brought about by tipping in consequence of the shifting of the centre of gravity owing to the change of distribution of the refrigerating liquid in the generator absorber on the one hand and of the condensate in the evaporator on the other hand, because after the liquid has once started flowing over, no further shifting of weights will take place. It is therefore impossible to cause an interruption of the heating if such interruption was not started previously. In the latter case the water is never removed from the evaporator, so that the residue in the evaporator which is not evaporated becomes larger and larger, until it renders the automatic restarting of the heating operation, which is caused by the shifting of the centre of gravity in consequence of evaporation and absorption, impossible, so that the machine comes to a standstill.

According to my present invention I obviate these drawbacks by causing the removal of the water in the evaporator to take

place at the end of the expulsion period, when the machine is changing over into the absorbing position, in contradistinction to the old machines, where the removal of the water is effected at the end of the absorption period when the machine is tipped into the generator position. When the machine is tipped, the liquid in the evaporator will swing from one end to the other and in doing so will drive part of the watery ammonia which has collected at the bottom, into a tube through which the ammonia can flow back into the absorber. I thus obtain a very simple construction and the new machine need only be tipped through a very small angle so that the evaporator can be filled entirely and is utilized very efficiently. On the other hand the tipping is in no way impaired by this construction, but can be varied at will within comparatively wide limits.

In the drawings affixed to this specification and forming part thereof a machine embodying my invention is illustrated diagrammatically by way of example,

Fig. 1 showing the machine in the generator position, while

Fig. 2 illustrates the absorber position.

Referring to the drawing, 1 is a generator absorber, 2 is an electric heating device, 3 is a pipe leading from the top of the generator absorber to a container 4. 5 is a pipe connecting the bottom of this container with the bottom of a vessel 6 partly filled with liquid, and 17 is a pipe leading from the upper part of this vessel to the bottom of the generator absorber 1. The bottom end of the pipe 5 extends into the liquid in the vessel 6. 7 is a separator communicating with the top of the vessel 6 and 8 is a pipe connecting this separator with a condenser 9, from which a pipe 10 leads to the uppermost of two evaporating vessels 11 and 12. A tube 13 mounted on the top of the lowermost evaporating vessel 12 extends from below into the uppermost evaporating vessel 11, projecting so far as to leave only a small clearance between its upper end and the cover of this vessel. This tube 13 is surrounded with a clearance by a tube 14, the upper end of which still slightly projects above the upper end of tube 13, while its lower end is spaced from the bottom of the vessel 11 so that gas and liquid are free to enter the space between the two tubes at

the top as well as at the bottom. A pipe 15 leading to the generator absorber 1 extends from below into the evaporating vessel 12, and a wider tube 16 surrounds the projecting end of tube 15 with a clearance, the upper end of tube 16 projecting above the upper end of pipe 15 and tapering inwards to form a cap. Also in this instance gas and liquid have free access to the space between the two tubes both at the top and at the bottom.

18 is a cooling water supply pipe and 19 is a distributing vessel supplied with water. According to the position of this vessel before or after a tipping operation the water is conducted through a pipe 20 to the condenser or through a pipe 21 to the absorber.

The whole system is arranged to be tipped about the centre of gravity 24, and in the position shown in Fig. 1 a contact device for the heater 2, in the position shown in Fig. 2 a stop 22 serve for limiting the tipping movement of the machine.

The operation of this machine is the following:

In the generating position shown in Fig. 1, heat is supplied to the solution in the generator absorber 1 by the heater 2 and the ammonia vapor is thereby expelled from the solution and rises in the tube 3. After passing through the container 4 the ammonia vapor enters the liquid in the vessel 6 through pipe 5, and after having been dried here passes through the liquid separator 7 and tube 8 into the condenser 9, where it is liquefied, the liquid flowing through the pipe 10 into the evaporating vessel 11, which is thus filled up to the top owing to the overflow tube 13. However, owing to the fact that the top end of tube 14 projects above the top end of tube 13, the liquid can enter the space between the two tubes from below so that with the liquid level rising further, only the watery ammonia solution which had remained over from a previous evaporation period, can first enter the space between the two tubes and in rising therein will flow over the top edge of tube 13 into the evaporating vessel 12.

50 However, this simple overflowing from one evaporator into a second one should not take place in order to allow the water still present in the bottom evaporating vessel 12 to return to the generator absorber 1, for in such case no tipping of the apparatus would take place. Means must be provided for starting the tipping before the evaporator 12 is entirely filled. When the apparatus changes over from the evaporating position 55 into the absorbing position, the liquid level will be higher with regard to the top end of tube 15 and the liquid in the evaporating vessel 12 will swing from one end of this vessel to the other, so that it will temporarily be higher at the left-hand end of this vessel.

sel than at the top end of the tube 15. This swinging of the liquid is favorable inasmuch as the liquid level in the outer tube 16 will follow this movement, the taper of the top end of tube 16 favoring such movement. In consequence thereof, if the moment of reversal of the apparatus is correctly adjusted, a certain part of the watery ammonia at the bottom of the evaporating vessel 12 will be driven into the pipe 15 and will flow back through this tube into the generator absorber 1. The quantity of liquid which flows from the evaporating vessel 11 through tube 13 into the evaporating vessel 12, after the apparatus has been tipped, will contribute to raise the liquid level in the vessel 12 and will thereby increase the overflow action described. In this manner the apparatus can be prevented from changing over only at the moment where in the absorption position the liquid level is also higher than the upper end of tube 15. A greater loss would be experienced if too much ammonia could flow back through pipe 15 into the generator absorber 1 and could increase the concentration of the solution contained therein instead of generating cold in the evaporating vessel 12 and in the upper part of the pipe 15.

In no case, however, is the evaporator liquid returned into the generator absorber in proportion as it enters the evaporator vessel, but during each tipping operation only a predetermined quantity of ammonia is returned, no matter whether it contained more or less water. This quantity can, however, be adjusted also in an already existing machine by simply shifting the centre of gravity 24 or by arranging compensating weights, so that each machine can be adjusted for different cooling water supplies.

During the absorption period the vapor flows from the evaporator through pipe 10, condenser 9 and pipe 8 into the vessel 6, which now serves as a liquid valve and from this vessel through pipe 17 into the generator absorber, where it enters below the liquid level.

I wish it to be understood that I do not desire to be limited to the particular operations nor to any details of construction shown and described for obvious modifications will occur to a person skilled in the art.

I claim:—

1. Absorption refrigerating machine comprising a generator absorber vessel, an evaporating vessel, and a condenser connected both with said generator absorber vessel and with said evaporating vessel, a pipe connecting the said vessels, the whole system being arranged to be tipped automatically about a point below its centre of gravity, in consequence of the passage of liquid from one to the other vessel in the course of operation of the machine and

means for causing liquid, which remained over in said evaporating vessel from an evaporating operation, to flow through said pipe into said generator absorber vessel 5 when the system is tipped at the end of the generating period.

2. Absorption refrigerating machine comprising a generator absorber vessel, an evaporating vessel, and a condenser connected both with said generator absorber vessel and with said evaporating vessel, a pipe connecting the said vessels having an extension projecting from below into said evaporating vessel and a tube surrounding 10 said extension and projecting beyond the upper end of said extension, while allowing access of liquid around its lower end and of gas around its upper end, the whole system being arranged to be tipped automatically about a point below its centre of gravity in consequence of the passage of liquid from one to the other vessel in the course of operation of the machine.

3. Absorption refrigerating machine comprising a generator absorber vessel, an evaporating vessel, and a condenser connected both with said generator absorber vessel and with said evaporating vessel, a 25

pipe connecting said vessels having an extension projecting from below into said evaporating vessel and a tube surrounding 30 said extension and projecting beyond the upper end of said extension, while allowing access of liquid around its lower end and of gas around its upper end, the said upper end 35 tapering inwards, the whole system being arranged to be tipped automatically about a point below its centre of gravity in consequence of the passage of liquid from one to the other vessel in the course of operation of 40 the machine

4. Absorption refrigerating machine comprising a generator-absorber vessel, two superposed evaporating vessels, a vapor connection from said generator-absorber vessel 45 to the upper evaporating vessel, a condenser forming a part of said connection, an overflow tube in said upper evaporating vessel extending downwards and ending in the top of said lower evaporating vessel, an overflow 50 tube in said lower vessel leading back into said generator-absorber vessel and a tube surrounding and projecting above the upper end of each overflow tube.

In testimony whereof I affix my signature.
ERICH KINDERMANN.
